ROLL PADDLE

William A. Norman, Chicago, Ill.

Application December 6, 1949, Serial No. 131,485

4 Claims. (Cl. 254—120)

1

My invention relates to roll paddles and similar devices.

My invention relates more particularly to improvements in the construction of prying bars or paddles as they are known in the trade, for use in moving a variety of types of material usually found in cylindrical rolls or packages. Materials of the type mentioned may include all types of printing paper rolls, linoleum, metal foils and other cylindrical packages easily susceptible to damage at the edges or corners unless handled so that no damage can be done. Among paper mills, printers, warehouses, railroads and other handlers of roll paper, damage to the side is frequently sustained due to improper or careless handling of the roll paper. One element which assists materially in cutting down or eliminating damage to the corner of the roll is a proper roll paddle, one sufficiently light and easy to handle so that all roll paper handlers will automatically reach for the paddle to use the same, and yet sufficiently strong and sturdy so that it will not easily become broken or get out of order.

The principal object of my invention is to provide an improved construction of roll paddle or similar device.

A further object is to provide a paddle of the type described which will be very light in weight, yet strong and rugged and capable of withstanding long and hard usage without becoming broken or out of order.

A further object of the invention is to provide a novel connection between the head and the neck of the paddle without the use of bolts, rivets or other fastening means whereby the connection is incapable of loosening.

A further object of the invention is to provide a novel construction of paddle wherein the operating or use head is constructed of cast magnesium and connected to a tubular metallic neck during the casting operation.

Other objects and advantages will be more apparent from the following description wherein reference is had to the accompanying drawings, upon which

Fig. 1 is a front elevational view of my improved roll paddle;

Fig. 2 is a side elevational view of the same;

Fig. 3 is a side elevational view showing the manner in which the paddle is used to move rolls of paper about; and

Fig. 4 is a changed position view showing the manner in which the roll paddle is applied to permit engagement of the upper flattened face of the head.

2

In the embodiment of the invention which I have chosen to illustrate and describe, I have shown a paddle which may essentially consist of three specific elements, a rod-like handle portion 10, a tubular sleeve or neck portion 12, and a head 14.

The handle 10 is preferably made of wood and slightly tapered toward its upper end, being also provided with an opening 15 so the same can be hung upon a nail or other support. The lower portion 17 of the wooden handle is turned down and adapted to be telescopically inserted into the tubular neck portion 12, being fastened therein by friction or by a wood screw 19 which may be employed if desired.

The neck portion 12 is preferably a steel tube approximately two inches in diameter, with a wall thickness of $\frac{1}{16}$ inch. The portion thereof which is connected to the paddle head is flattened by having the two side walls 20 and 22 tapered to a point 24, in which condition the tubular neck is set into the mold and the head 14 is poured about the same so that after the head is cast it is integrally connected to the neck portion and the two parts can not become separated except by breaking either the head or the neck portion.

The head 14 is preferably cast of as light a metal as possible, yet in view of the fact that it is the working portion of the paddle, it is necessary that it be tough and hard as possible. Accordingly, I prefer to cast the same of magnesium which I have found to be very satisfactory for the purposes herein described.

The head 14, as shown, is provided with a comparatively flat face 26 terminating in the nose 28, the material extending therefrom in a taper as shown to form the back or heel portion 30 thereof. The face 26 is somewhat wider than the neck 12 or handle 10, thus effecting more of a gripping space for engaging cylindrical rolls or similar packages.

Upon the upper end of the face 26 I have provided a further flattened portion 32. This is for engaging a roll of paper P with the same when the paddle is in the position shown in Fig. 4, the purpose of the flattened face being to prevent and edge engagement at any time with the surface of the roll of paper P.

I have found that with the construction shown, wherein a magnesium head, a steel neck and a wooden handle are assembled in the manner described, the possibility of breakage is extremely remote. Since most of the breakage of roll paddles occurs just above the head 14 in the tubular neck portion 12, the provision of the steel tubu-

lar member affords at this point a maximum of strength so that such breakage as occurs in wooden paddles is not possible with the construction provided.

While I have illustrated and described a specific embodiment of the invention, it will be apparent to those skilled in the art that changes and modifications may be made in the exact details shown, and I do not wish to be limited in any particular; rather what I desire to secure and protect by Letters Patent of the United States is:

1. A paddle for moving rolls of paper comprising a magnesium head, an elongated tubular neck extending therefrom, a wooden handle portion connected thereto, said head having a nose at right angles to said handle, a generally flat arcuately shaped face and a collar portion encircling the end of said neck, the end of said neck being flattened out and embedded in said head.

2. A paddle of the type described having a flattened and widened head terminating in a nose portion, a collar on said head, a tubular neck portion extending therefrom, and a handle having a portion telescoped into the end of said neck portion, said tubular neck being flattened at its end with the head cast about the same to integrally connect said head and said neck.

3. A comparatively light yet sturdy paddle of the type described having in combination a head, a neck and a handle portion, said handle portion

being a wooden rod having a reduced end, said neck comprising a metallic tube with the reduced end of said wooden rod telescoped into one end of the same, the other end being flattened with the head cast about the same to integrally connect said head and neck.

4. A comparatively light yet sturdy paddle of the type described having in combination a head, a neck and a handle portion, said handle portion being a wooden rod having a reduced end, said neck comprising a metallic tube with the reduced end of said wooden rod telescoped into one end of the same, the other end being flattened with the head cast about the same to integrally connect said head and neck, said head having a nose portion at the lower edge of its face.

WILLIAM A. NORMAN.
